DYNAMIC FACADE SYSTEM FOR
CONTROLLING SHADING

TECHNICAL FIELD

The present invention relates to a dynamic facade system for controlling shading.

BACKGROUND

One of the most recent and important research pathways for architecture and construction engineering has been controlling the internal environment of buildings in order to reach a certain level of comfort for the user. Various factors, such as temperature, lighting and humidity, are included in this picture.

Control is usually obtained through traditional systems that consume a significant amount of power. Within the context of green buildings aiming for zero emissions, this is no longer sustainable and therefore new paradigms are required.

Two main requirements have been identified for the application selected.

The system should respect the environment, i.e., from a technical viewpoint, it should require (almost) zero energy to be operated. This would allow the building's emissions to be limited and its energy efficiency to be increased.

The other fundamental requirement is the controllability by the user: the system should be able to respond to user input in order to comply with their needs. This is essential to reach an acceptable individual level of comfort, the conditions of which can differ, depending on the contingent situation, from those programmed.

It is immediately clear that these two main requirements are deeply conflicting: the zero-energy paradigm would require a totally passive system, which self-regulates as a function of a given external input and does not respond to the user's wishes or needs, while controllability entails an active feedback, which naturally requires energy. This opposition is indeed a major obstacle for the practical implementation of intelligent passive facades.

SUMMARY

The object of the present invention is to provide a dynamic facade system for controlling shading that requires very little energy in order to be operated.

Another object is to obtain an adequate level of comfort in different environmental conditions.

A further object is to obtain a good level of controllability by the user.

In accordance with the present invention, these and other objects still are achieved by a dynamic facade system for controlling shading, characterized in that said facade system comprises a block composed of an outer glass panel, an intermediate framework inside which a series of steel cables are fixed, and an inner framework that incorporates an inner glass panel; said outer glass panel, said intermediate framework and said inner framework being joined to one another; said system comprises modules fixed on said cables; said modules comprise a first outer structure; said first outer structure comprises a frame and at least one first wing; said at least one first wing is movably connected to said frame by means of a first hinge; characterized in that said first hinge is made with a shape memory element with passive configuration.

2

Further features of the invention are described in the dependent claims.

The advantages of this solution with respect to prior art solutions are several.

With the present solution, an intelligent dynamic facade is obtained, which integrates a solar shading system configured as structures with variable geometry and with shape memory. In the system proposed, sensitivity to sunlight and autonomous drive are combined with the essential features of user controllability and interaction.

Drawing its inspiration from nature, just as sunflowers turn their petals in response to sunlight, the designed shading system dynamically adapts its wings to the incoming radiation, regulating their folding/opening configuration.

This mechanism is possible due to the use of shape memory materials that possess the unique feature of memorising shapes that can be recovered through the application of external stimuli.

The shape memory polymer layer allows completely autonomous passive control of the internal conditions and zero energy drive. Moreover, the integration of an opaque internal layer activated by shape memory alloys (SMA), ensures the possible implementation of the resulting structure in real buildings, balancing comfort, wellbeing and performance (adaptive comfort) and allowing personal control of the living and working environments.

The invention allows an increase in the building's performance both in energy terms and in terms of comfort: while the outer structure allows autonomous regulation with zero energy impact, a further inner structure allows the adaptive user comfort paradigm to be applied.

Finally, its modularity allows maintenance costs to be reduced, while also facilitating accessibility.

The inner structure acts in parallel and as a complementary and opposing layer with the outer structure.

The outer structure makes it possible to obtain a device that is driven automatically based on the external environmental conditions, without the need for any interaction by the user.

BRIEF DESCRIPTION OF THE DRAWINGS

The features and the advantages of the present invention will be apparent from the detailed description of a practical embodiment thereof, illustrated by way of non-limiting example in the accompanying drawings, wherein:

FIG. 1 schematically shows a module of a dynamic facade system for controlling shading, in accordance with the present invention;

FIG. 2 schematically shows a drive system of an inner structure of a module of a dynamic facade system for controlling shading, in three different positions, in accordance with the present invention;

FIG. 3 schematically shows an electrical circuit of shape memory springs used as hinges of an inner structure of a module of a dynamic facade system for controlling shading, in accordance with the present invention;

FIG. 4 schematically shows the possible positions of a module of a dynamic facade system for controlling shading, in accordance with the present invention;

FIG. 5 schematically shows a system for containing a plurality of modules of a dynamic facade system for controlling shading, in accordance with the present invention.

DETAILED DESCRIPTION

With reference to the accompanying figures, a dynamic facade system for controlling shading, in accordance with a

preferred embodiment of the present invention, is composed of a plurality of modules **10** that comprise a square framework **11** that is used to support an outer structure **12** and an inner structure **13**.

The outer structure **12** comprises a frame-shaped square base **15**. The base **15** can be made of plastic materials, wood or metal alloys.

A triangular-shaped wing **16** is hinged to each side of the base **15**. The dimension of the wing **16** is such that by moving the four wings **16** toward one another, this forms a pyramid, with a closing angle, for example, of 60°, for aesthetic purposes, although other inclinations are possible.

The wings **16** are hinged to the base **15** by means of flexible sheets that form a hinge **20**. Possible other plastic or metal hinges that are free to move can be used to reinforce the connection between the parts.

The wings **16** are preferably made of a translucent (partially transparent) plastic material, such as polycarbonate sheets, to prevent excessive darkening of the interiors when they are closed; however, other types of materials and opacities, such as perforated metal or plastic material, can be used, according to need.

The hinges **20** composed of flexible rectangular sheets are made with a shape memory element with passive configuration, such as a shape memory polymer (SMP), for example the membrane called Nafion™ N1110.

The modules **10** are positioned on the building facade, so that the SMP hinges **20** are illuminated by sunlight and hence heated by it or in any case placed in an environment whose temperature varies as the solar radiation varies.

The SMP hinges **20** have been previously trained to allow passage between two configurations, depending on the temperature. Completely open, with an inclination of approximately 90°, relative to the base plane, for low temperatures, i.e. low radiation. Completely closed, with a slope of 60°, at high temperatures, as a consequence of direct solar radiation.

The transition temperature of the SMP should be in the range 40-70° C., or more preferably 50-60° C., which represent the normal temperatures reached in facades in daily operating conditions.

In an embodiment, the base **15** is a square having a side of around 33 cm. The triangular wings **16** have a height of around 33 cm.

The SMP hinges **20**, preferably one per wing **16**, have a dimension, for example, of 100×60 mm.

The inner structure **13** is composed of four wings **21** which if placed side-by-side, i.e., in the closed position, form a square with same dimensions as the square framework **11**.

The wings **21** are made of an opaque material (through which light radiation cannot pass), for example a black acrylic material such as PMMA, to block sunlight when closed.

The wings **21** are fixed to the square framework **11** by means of two hinges **22** per side, formed of springs **23** and **24** produced with an actuator made of shape memory alloy (SMA), for example 0.5 mm wires made of a NiTi alloy.

Each hinge **22** is produced by two opposed and adjacent springs **23** and **24**. The spring **23** is wound in one direction and the spring **24** is wound in the opposite direction.

The springs **23** and **24** are connected to the wings **21** extending them. In this way a constant tension is created, producing a moment that will be present in both.

However, in this case the total moment is approximately zero due to balancing and the wing is held in a position of constant equilibrium that, with reference to the resulting

positioning, corresponds to the closed position (FIG. 2a) where the inner structure prevents the solar radiation from entering.

The springs of the shape memory alloy hinges **22** behave as simple resistors and can be driven by electricity or alternatively by controlled temperature changes.

The material heats up, exceeds the activation temperature and returns to a previously memorised shape.

Therefore, two electrical wires are connected to each spring, one per end, which carry a current generated respectively by a generator **25** and **26** controlled by means of a respective switch **27** and **28**.

By operating the switch **27**, the passage of current heats the spring **23** and consequently the wing **21** is positioned in the open position of FIG. 2b.

By operating the switch **28**, the passage of current heats the spring **24** and consequently the wing **21** is positioned in the retracted position of FIG. 2c.

To return it once again to the closed position of FIG. 2a, the opposite switch to the one previously operated is operated.

The combination of the outer structure **12**, passive, and of the inner structure **13**, activated by the user, allow different operating combinations of the module **10**. Other combinations between the parts are possible based on the purpose of the building, by making slight changes to the configuration of both the passive and controlled drives.

Outer structure **12** closed and inner structure **13** open internally, situation of FIG. 4a, which allows the passage of light filtered by the outer structure **12**.

Outer structure **12** open and inner structure **13** open internally, situation of FIG. 4b, which allows the passage of light.

Outer structure **12** open and inner structure **13** closed, situation of FIG. 4c, which does not allow the passage of light.

Outer structure **12** open and inner structure **13** open externally, situation of FIG. 4d, which allows the passage of light.

To create a facade by means of the modules **10** a prefabricated block **30** has been produced.

The block **30** is composed of an outer glass panel **31**, an intermediate framework **32** inside which a series of steel cables are fixed, preferably arranged vertically, and an inner framework **34** that incorporates an inner glass panel **35**. These are all joined to one another to form a ventilated cavity as the intermediate framework has upper **37** and lower **36** ventilation holes.

The side walls of the modules **10** are fixed on the cables **33**.

As the block **30** is a natural ventilation system, the air circulates by means of two mechanisms.

The wind that flows over the facade generates differences in pressure between the lower ventilation holes **36** and the upper ventilation holes **37**, which brings about movement of the air inside.

The air flowing in through the holes **36** is heated by the sun, becoming less dense and thermally floating, rises and is expelled through the upper holes **37**.

The block **30** can be made with different outer shapes, such as square, triangular, etc. Other coupling systems of the modules **10** can be used in place of the cables **33**, such as another steel or acrylic substructure.

The block **30** can be ventilated in a forced manner, or be completely sealed if the temperatures reached inside allow its operation.

5

To create a facade, in place of the blocks 30 other methods can be used, such as fixing the modules 10 directly to transparent walls, if necessary, avoiding retracted positioning of the inner structure 13, as in the situations of FIGS. 4a and 4b.

In an alternative and simpler embodiment, the module 10 can be composed solely of the outer structure 12 and hence operate at zero energy consumption.

In the embodiment shown, both the outer structure and the inner structure comprise four triangular-shaped wings. These wings can also have other shapes and their number can differ, also differing in number between the outer structure and the inner structure, according to needs.

A single wing, or two, four or eight wings can be used, having respective shapes to allow complete closing of the module. In this case, the orientation of the sun's rays must be taken into account as the number or shape could influence the shade on the contiguous modules.

The square module envisaged can also have different geometrical shapes and different dimensions.

The hinges 22 are produced, in the example described, with an actuator made of shape memory alloy, but other actuators, such as electric actuators, can be used.

Operation of the invention is evident to the person skilled in the art from the description and in particular is as follows.

When the facade produced in accordance with the present invention is assembled, the sun's rays will directly influence opening and partial or complete closing of the wings 16 of the outer structure 12 depending on the features of the hinges 20 and on their temperature.

The user will normally maintain the wings 21 in neutral position, but can further regulate the amount of light reached inside the building by controlling operation of the hinges 22 electrically.

The invention claimed is:

1. A dynamic facade system for controlling shading, characterized in that said facade system comprises a block (30) composed of an outer glass panel (31), an intermediate framework (32) inside which a series of steel cables (33) are fixed, and an inner framework (34) that incorporates an inner

6

glass panel (35); said outer glass panel (31), said intermediate framework (32) and said inner framework (34) being joined to one another; said system comprises modules (10) fixed on said cables (33); said modules (10) comprise a first outer structure (12); said first outer structure (12) comprises a frame-shaped square base (15) and at least one first wing (16); said at least one first wing (16) is movably connected to said frame-shaped square base (15) by means of a first hinge (20); characterized in that said first hinge (20) is made with a shape memory element with passive configuration.

2. The system in accordance with claim 1, characterized in that said at least one first wing (16) has a same dimension as said frame-shaped square base (15).

3. The system in accordance with claim 1, characterized in that said at least one first wing (16) comprises four triangular-shaped first wings (16).

4. The system in accordance with claim 1, characterized by comprising a second inner structure (13) having at least one second wing (21); said at least one second wing (21) is movably fixed to said frame-shaped square base (15) by means of a second hinge (22).

5. The system in accordance with claim 4, characterized in that said second hinge (22) is produced with an actuator made of shape memory alloy.

6. The system in accordance with claim 4, characterized in that said second hinge (22) comprises a first spring (23) and a second spring (24) opposite and alongside one another; said first spring (23) is wound in one direction and said second spring (24) is wound in the opposite direction.

7. The system in accordance with claim 1, characterized in that said at least one first wing (16) is made of a translucent plastic material.

8. The system in accordance with claim 1, characterized in that said at least one second wing (21) is made of an opaque material.

9. The system in accordance with claim 1, characterized in that said facade system comprises a plurality of said first outer structures (12).
